[57] CLAIM

The ornamental design for a spool for winding string and wire, as shown and described.

DESCRIPTION

FIG. 1 is a front elevational view of a spool for winding string and wire showing my new design;

FIG. 2 is a top plan view;

FIG. 3 is a left side elevational view;

FIG. 4 is a rear elevational view rotated 180°;

FIG. 5 is a right side elevational in rotated position;

FIG. 6 is a front elevational view of a spool for winding string and wire showing a modified form of my new design;

FIG. 7 is a top plan view thereof;

FIG. 8 is a left side elevational view thereof;

FIG. 9 is a rear elevational view thereof rotated 180°; and,

FIG. 10 is a right side elevational view thereof in the rotated position.

FIG. 2

FIG. 3
